Primary Examiner — Thomas Johannes*Assistant Examiner* — Lauren McVey(74) *Attorney, Agent, or Firm* — Price Heneveld LLP(57) **CLAIM**

The ornamental design for a surgical blade loader, as shown and described.

DESCRIPTION

FIG. 1 is a front perspective view of a surgical blade loader, showing our new design;

FIG. 2 is a front elevation view thereof;

FIG. 3 is a rear elevation view thereof;

FIG. 4 is a right side elevation view thereof;

FIG. 5 is a left side elevation view thereof;

FIG. 6 is a top plan view thereof;

FIG. 7 is a bottom plan view thereof; and,

FIG. 8 is a rear perspective view thereof.

The broken lines immediately adjacent the shaded areas represent the bounds of the claimed design while all other broken lines are directed to environment and are for illustrative purposes only; the broken lines form no part of the claimed design. In addition, the unshaded surfaces that directly adjoin the claimed solid line edges form no part of the claimed design.

The "Bard-Parker" lettering and icon forming part of the disclosure are registered trademarks of ASPEN SURGICAL PRODUCTS, INC.
